UNITED STATES PATENT OFFICE.

FRANK KUHN, OF DETROIT, MICHIGAN.

ELECTRICAL HEATER.

1,107,322.

Specification of Letters Patent. Patented Aug. 18, 1914.

Application filed December 27, 1913. Serial No. 808,955.

To all whom it may concern:

Be it known that I, FRANK KUHN, a citizen of the United States of America, residing at Detroit, in the county of Wayne 5 and State of Michigan, have invented certain new and useful Improvements in Electrical Heaters, of which the following is a specification, reference being had therein to the accompanying drawings.

10 The invention relates to electric heaters particularly designed for use as radiators, foot warmers, etc., and the invention consists in various features of construction as hereinafter set forth.

15 In the drawings: Figure 1 is a longitudinal section through the heater; Fig. 2 is a perspective view of a portion of the base of the heater case detached, showing the manner of mounting the heating element 20 thereon; Fig. 3 is a cross section; and Fig. 4 is a similar view showing a modified construction.

25 A and A' are two end members, preferably formed of castings, and provided with the inwardly-extending flange B.

C is a perforated sheet metal casing member bent to form the top and sides of the case and to fit within the flanges B of the members A and A'.

30 D is a sheet metal base member which is secured to lugs E on the end members A and A' by suitable securing devices such as the screws F. The sides of this base are provided with upturned flanges G, which 35 overlap the perforated case C and abut against the flanges B to form a finish.

Upon the base member D is mounted the heating unit or units. These are preferably supported by brackets H which, as shown, 40 are Z-shaped strips of metal, having their lower flanges H' spot-welded or otherwise secured to the base, while their upper flanges H² form a support for the heating element. This heating element I is of the flat armored 45 type, and has its end portions beveled at I' upon opposite sides of the terminal contact J. The element may be secured by bolts K passing through apertures in the flange H², and carrying clamping washers L which 50 overlap the element and bind the same upon the brackets H.

The terminal conductors can be carried out through the bottom of the core as indicated at M in Fig. 1. I have, however, in 55 Fig. 4, shown a slightly modified construction wherein the terminal connectors are

carried out of the casing through one of the end members A such as indicated at N.

With the construction as described, air is freely admitted through the perforated casing, both below and above the heating units I, and will then pass outward through the top of the case. Direct radiation from said units will also pass upward and consequently the heater is particularly adapted 65 for use as a foot-warmer.

What I claim as my invention is,—

1. An electric heater, comprising end members, a perforated casing engaging said members, a bottom plate detachably secured 70 to said end members, and a heating unit mounted on said bottom plate and supported thereby within said perforated casing.

2. An electric heater, comprising flanged end members, a perforated casing engaging 75 said end members adjacent to the flanges thereof, a base plate extending between said end members having side flanges overlapping the lower edges of said perforated casing and abutting against the flanges of 80 said end members, means for detachably securing said bottom plate to said end members, and an electric heating unit mounted on said bottom plate and supported above the same in the space within said perforated 85 casing.

3. An electric heater, comprising end members, a perforated casing extending between said end members, a detachable bottom plate, supporting brackets secured to 90 and extending above said bottom plate, and an electric heating unit clamped upon said supporting brackets and attachable and detachable with said bottom plate from said casing and end members. 95

4. An electric heater, comprising end members having marginal flanges, bottom lugs and depending feet, a perforated casing extending between said end members and fitting within said marginal flange, a 100 bottom plate detachably secured to said bottom lugs, and provided with side flanges overlapping the lower edges of said perforated casing and abutting against the marginal flanges of said end members, and an 105 electric heating unit mounted on said bottom plate above the same and within the space inclosed by said perforated casing.

5. An electric heater, comprising end members provided with marginal flanges, 110 depending feet and bottom lugs, the top flanges being inclined, a perforated casing

- extending between said end members, fitting within said marginal flanges and having a corresponding inclined top, a bottom plate detachably secured to said bottom lugs, and
- 5 a plurality of electric heating units mounted upon said bottom plate in stepped relation to each other and located within the space inclosed by said perforated casing.

In testimony whereof I affix my signature in presence of two witnesses.

FRANK KUHN.
